UNITED STATES PATENT OFFICE.

LUIGI ANECHIARICO, OF ASBURY PARK, NEW JERSEY.

STEPLADDER.

1,354,370.

Specification of Letters Patent. Patented Sept. 28, 1920.

Application filed April 14, 1919. Serial No. 239,979.

To all whom it may concern:

Be it known that I, LUIGI ANECHIARICO, a citizen of United States, residing at 1516 Asbury avenue, Asbury Park, in the county 5 of Monmouth and State of New Jersey, have invented new and useful Improvements in Stepladders, of which the following is a specification.

The invention relates to step-ladders and 10 has for an object to provide a step-ladder of a simple construction, consisting of few parts that can be cheaply manufactured and readily assembled, and also contemplates the use of suitable platforms or ledges together 15 with operating devices for shifting the ladder from one place to another, thus providing a structure particularly adaptable for the use of painters, paper-hangers and like interior decorators.

20 Among other features the invention comprehends a step-ladder which when folded will be in a compact form so that it can be easily carried from one place to another and which can be readily set up in position for 25 use, the platform employed in connection with the step-ladder, being also of a foldable nature, and when open for use, supplying an efficient support for the materials to be used by the decorator in his work.

30 In the further disclosure of the invention, reference is to be had to the accompanying drawings, constituting a part of this specification, in which similar characters of reference denote corresponding parts in all the 35 views, and in which,

Figure 1—is a side elevation of the step-ladder, with parts broken away or in section.

Fig. 2—is a vertical sectional view taken 40 on the line 2—2 in Fig. 1, looking in the direction of the arrows.

Fig. 3—is a horizontal sectional view taken on the line 3—3 in Fig. 1, looking in the direction of the arrows.

45 Fig. 4—is a side elevation of the ladder as it appears when folded or closed, and

Fig. 5—is a fragmentary detail partly in elevation and partly in section showing the foldable arrangement of the platform and 50 the supplementary extension.

Referring more particularly to the views the main parts of the ladder consist of a ladder section 10, a prop section 11 suitably hinged to the ladder section 10 at 12, and a 55 support 13 for a platform 14, the support 13 being suitably hinged at 15 to the lower end

of the prop section 11. Suitable bearings 16 project from cap pieces 17, fitted over the upper and lower ends of the ladder section 10 and journaled in these bearings are 60 vertical shafts or rods 18, the upper ends of which terminate in handles 19 and the lower ends of which carry toothed beveled wheels 20, meshing with the beveled portions 21 of rollers 22, mounted on the lower 65 cap pieces and acting as casters or supports for the ladder section, the prop section being also provided with rollers 23, suitably mounted on the lower ends thereof. With this mechanism it will be seen that by turning one or both of the handles 19 that the operator, standing upon the ladder section, can readily convey the step-ladder from one place to another or swing it around in a 70 pivotal manner without requiring him to remove himself from the ladder in order to accomplish this result.

The platform support 13 carries a suitable cross piece 24, adapted to form a rest or support for one end of a ledge 25 which is 80 supplementary to a second ledge 26, and in fact forms a continuation of the latter, when set up. This supplementary ledge 25, is formed of a series of parallel strips 27 with the inner ends of said strips pivoted on a 85 horizontal cross rod 28, suitably secured in bearings 29 on the prop section. A second cross rod 30 is secured to the ladder section and pivoted thereon are a series of strips 31 having their outer extremities notched as 90 at 32 to fit over the cross rod 28, whereas other strips 33 are pivoted to the cross rod 28 and are notched as at 34, to fit over the cross rod 30 and these strips 31, 33, when the ladder is set up, being adapted to lie 95 relatively parallel and horizontal and form the complete ledge 26.

By having the various strips of the ledge and supplementary ledge disposed and arranged as mentioned, it will be seen that 100 when the ladder is folded up or closed as in Fig. 4, the ledge and supplementary ledge will also tend to be relatively folded and will not project any great distance beyond the sides of the ladder section and platform 105 support when the same are in relatively closed position.

By reference to Fig. 3, it will of course be seen that the strips 31, 33, have their medial portions pivoted to a cross rod 35 so 110 that the relative folding of the strips forming the main ledge will be accomplished in

the closing of the ladder and it will of course be apparent that the supplementary ledge 25 including an end cross piece 36, will tend to hold the platform support in a vertical position and prevent it from swinging outwardly from the ladder after the same has been set up.

Having described my invention, I claim—

1. In a ladder the combination with a ladder section and a prop section hinged thereto, of a foldable ledge mounted on the ladder section and prop section, said ledge consisting of a series of strips extending in one direction from the ladder section and an other series of strips extending in the opposite direction from the prop section, the first series of strips being hinged upon the ladder section and the second series hinged upon the prop section with the strips in one series hinged relatively to the strips in the other series, between said ladder section and said prop section.
2. In a ladder the combination with a ladder section and a prop section hinged thereto, of a foldable ledge mounted on the ladder section and prop section, said ledge consisting of a series of strips extending in one direction from the ladder section and an other series of strips extending in the opposite direction from the prop section, the first series of strips being hinged upon the ladder section and the second series hinged upon the prop section with the strips in one series hinged relatively to the strips in the other series, between said ladder section and said prop section, and a supplementary ledge formed of a series of strips, said supplementary ledge being mounted to swing upon the prop section to lie in line with the

main ledge when the ladder and prop sections are set up.

3. In a ladder the combination with a ladder section and a prop section for supporting the ladder section, of a cross rod on the ladder section, a cross rod on the prop section, a ledge consisting of a plurality of series of strips, one of said series of strips being hinged upon the cross rod on the ladder section and the other series of strips being hinged upon the cross rod of the prop section, with the series of strips on the ladder section adapted to engage the cross rod on the prop section and the series of strips on the prop section, adapted to engage the cross rod on the ladder section.

4. In a ladder the combination with a ladder section and a prop section for supporting the ladder section, of a cross rod on the ladder section, a cross rod on the prop section, a ledge consisting of a plurality of series of strips, one of said series of strips being hinged upon the cross rod of the ladder section and the other series of strips being hinged upon the cross rod of the prop section, with the series of strips on the ladder section adapted to engage the cross rod on the prop section and the series of strips on the prop section, adapted to engage the cross rod on the ladder section, a platform support hinged to the prop section and a supplementary ledge mounted to swing adjacent the main ledge, and adapted for engagement with the platform support for supporting the supplementary ledge in the horizontal plane of the main ledge when the ladder and prop sections are in relatively open position.

In testimony whereof I affix my signature.

LUIGI ANECHIARICO.
